CALCULATING MACHINE

Torsten Lagerman, Goteborg, Sweden

Application May 18, 1938, Serial No. 208,679
In Germany May 28, 1937

2 Claims. (Cl. 235—79)

The present invention relates to calculating machines, and more particularly to calculating machines of the type which are provided with a rotor composed of setting disks each having a number of shiftable teeth, or with some other similar mechanism for setting up the items to be introduced into the totalizer, and which are also equipped with a key-board, preferably comprising ten keys, for adjusting the shiftable teeth of the setting disks through the intermedium of setting members. The invention has for its object to provide a machine of the kind set forth of particularly simple and inexpensive construction.

Calculating machines having a setting mechanism composed of setting disks with adjustable teeth and a key-board comprising ten keys are previously known in which each setting disk is provided, as in similar machines having setting levers, with a rotatable curved disk, which, upon depression of a key, is turned more or less through the intermediary of movement transmitting members in correspondence with the numeral value of the key. Also other machines of the setting disk type having a key-board comprising ten keys are known but such machines are all of a rather complicated construction.

Furthermore, calculating machines the setting mechanism of which comprises setting disks with shiftable teeth and which have a complete key-board are known in which there are allotted to each setting disk a number of laterally turnable setting members, for example four such members, which are actuated by the keys in the row of keys appertaining to the corresponding setting disk through the intermediary of a series of movement transmitting members and which upon actuation shift a corresponding setting-disk-tooth or group of teeth in a lateral direction.

According to the present invention the setting members controlled by the keys are arranged in such known manner, each opposite a corresponding tooth or group of teeth in the setting disk being in its setting position, as to be capable of causing the corresponding teeth or groups of teeth to be shifted, preferably in an axial direction, without turning any part of the setting disk about its axis. The invention is characterized in that the setting members consist of pins or the like which are displaceable in a plane that is parallel with the plane of the respective setting disk and are adapted, upon displacement, to engage with the corresponding teeth or groups of teeth or to be brought into working

positions in preparedness for engagement with said teeth or groups of teeth. Since the setting pins are thus movable in a plane that is parallel with the plane of movement of the keys said pins can be actuated in a simple manner, for example through the intermediary of bails which are movable in parallel with said plane and are actuated directly by the key arm. In a ten-key machine according to the invention the total number of setting pins can be reduced to four, for example, thereby considerably reducing the total number of parts of the setting mechanism. Preferably the setting pins are so arranged that the actuation thereof through the keys will bring them into working or stop positions positioned axially with respect to the corresponding teeth or groups of teeth, the stop pins being brought into actual engagement with the teeth to be set up through a step-wise displacement of the setting disk rotor relatively to the pins. Such construction involves the advantage that the setting-up of the teeth will be effected through the driving power of the stepping mechanism, resulting in that the setting pins, which themselves can be made easily movable, become readily shiftable so that a very slight pressure on the key will suffice to depress the same.

The invention will now be described more in detail having reference to the accompanying drawings which show an embodiment of the invention. The drawings show substantially only such parts of the calculating machine, to which the invention directly applies, in that the machine can be constructed for the rest in a manner known per se. In the drawings

Figure 1 shows the setting disk rotor and certain parts cooperating therewith, partly in front view and partly in section on the line 1—1 in Figure 3;

Figure 2 shows the same parts in top view, the rotor being partly broken away;

Figure 3 shows a section taken at right angles to the axis of rotation of the rotor;

Figure 4 is a detail shown on a larger scale;

Figure 5 shows another section taken at right angles to the axis of the rotor;

Figure 6 shows a modified detail; and

Fig. 6a shows the modified detail of Fig. 6 in inoperative position.

The rotor 1 is supported by a shaft 2 which is mounted for rotation in the frame, a crank or other driving means, for instance an electric motor, being provided to rotate the shaft. The rotor is displaceable axially on the shaft and is

rotatable together therewith. It is composed in known manner of a number of setting disks 3, each of said disks being provided with nine adjustable or settable teeth 4 which are shown only partly on the drawings. Some of the teeth of each disk are combined to form groups of teeth having fixed relation to each other so as to be adjustable in common, said groups of teeth being preferably combined to form toothed sectors. In the example shown five teeth are combined to form a toothed sector 5, and two teeth are combined to form a smaller toothed sector 6. The two remaining teeth are individually adjustable and consist of rods or pins 7 and 8. All the teeth and toothed sectors in each setting disk are pivoted with slight play on a circularly bent spindle 9 which is inserted between the two halves 10 (Figure 4) of which each setting disk 3 is composed. The teeth or toothed sectors respectively are positioned in recesses between the halves 10 and are provided each with a spring actuated stop, said stop consisting of a spring actuated ball 11 which is positioned in a bore and retained therein by a stud 12 on the tooth or sector, which is held by the stop in either one of two limit positions (compare Figure 4), the position shown in full lines being the inoperative position and the position shown in dot-and-dash lines being the operative position of the teeth or toothed sectors.

In the shown example the setting members consist of four pins 5', 6', 7', 8' which are arranged in a row extending at right angles to the rotor shaft and are supported in a holder 13 fixed to the frame, the pins being displaceable in said holder in their vertical longitudinal directions. Each stop pin is normally held in a lower position by a spring 14. The stop pins are positioned substantially in the plane of the setting disk which is in order to be adjusted so that when the rotor occupies its starting position the stop pins will be positioned approximately right in front of the outermost setting disk at the left hand end of the rotor. As will be clear from Figure 3, the pin 5' is arranged to cooperate with the toothed sector 5 comprising five teeth, the pin 6' cooperates with the toothed sector 6 comprising two teeth, and the pins 7' and 8' cooperate each with an appertaining one of the individually adjustable teeth 7 and 8.

The actuation of the setting pins through the ten numeral keys 15, which are disposed at the front side of the machine, is effected through the intermediary of four bails 5'', 6'', 7'', 8'' which are journalled in the frame, the middle portions of said bails extending below and appertaining one of the setting pins and above the inner ends of the keys. Each one of the keys, with the exception of the zero key, is provided at each point where it crosses any one of the bails 5''-8'' with which it is supposed to cooperate with a raised portion 16 which, upon the depressing of the key, lifts the bail and consequently also the corresponding setting pin. As will be clear from Figure 2, the 9-key is provided with four raised portions which will lift, upon depressing of the key, all four bails 5''-8'' and thus all four setting pins 5'-8', while the 8-key has raised portions under the bails 5'', 6'' and 8'', the 7-key is adapted to actuate the bails 5'' and 6'' and thus the pins 5' and 6', the 6-key actuates the bails 5'' and 8'', the 5-key only the bail 5'', the 4-key the bails 6'', 7'' and 8'', 75

the 3-key the bails 6'' and 7'', the 2-key the bails 7'' and 8'', and the 1-key the bail 8''.

Extending above the inner ends of all the keys, thus also above the 0-key, is a bow 17 which carries a detent 18 turnable on a vertical pivot and also a detent 19 fixedly secured to the bow and positioned adjacent to and somewhat lower than the detent 18, said two detents being adapted to cooperate, for the purpose of effecting the step-wise movement of the rotor or barrel, with a rack 20 secured at the ends of two arms 21, 22 extending forwards and downwards from the end pieces of the rotor. The pivoted detent 18 is normally in engagement with one of the teeth of the rack 20, thereby preventing the rotor from being displaced to the left under the action of a powerful spring 23 which acts on a lever 24 the bifurcated upper end of which engages with a pin 25 disposed on the arm extending from the right hand end piece of the rotor. When, upon depression of any one of the keys, the bow 17 is lifted, the detent 18 will be moved out of engagement with the rack 20 while at the same time the fixed detent 19 will be moved into the following space between the teeth (Figure 2) and into the path of the following tooth on the rack, so that during the depression of the key the rotor will move one half step to the left under the action of the spring 23. Provided that the depressed key is not the zero key but any one of the keys which cooperate with the bails 5''-8'', a number of teeth 4 on the nearest setting disk corresponding to the numeral value of the key will then be moved against the stop pins raised by the key and thus be brought into operative position, said teeth being forced by the stop pins to snap over to the right to their operative positions, as shown in Figure 4 with dot-and-dash lines.

During the return movement of the key the stop pins raised thereby are lowered into their starting positions under the action of the spring 14. Furthermore, the detent 19 fixedly secured to the bow 17 will be gradually moved out of engagement with the rack 20, the pivoted detent 18 being at the same time moved into the same space between the teeth of the locking bar, so that at the end of the return movement of the key the rotor will be moved a further half step. The next setting disk will now be in a position for setting up its teeth.

The indicating mechanism consists of a number of numeral sectors 27 pivoted on a shaft 28 supported by the arm 21, 22 and each provided at its front face with the numerals 0 to 9. According to the position of the numeral sectors a corresponding numeral will appear in numeral opening 29 provided in the machine casing. The numeral sectors 27 participate in the stepwise movement of the rotor and will therefore one after the other be brought into setting position right opposite a setting arm 30 rigidly secured to a bar 31 which is pivoted on the same shaft as the keys and extends above the same. Upon depressing any one of the keys with the exception of the zero key the key will press with a finger 33, which extends upwards and rearwards and the length of which is determined with regard to the numerical value of the key, against the bar 31, said bar being rocked more or less to the left in accordance with the numerical value of the key. The arm 30 then presses against a projection 32 on the opposite numeral sector 27, swinging the latter so much upwards that the numeral corresponding to the key will appear in the corresponding numeral

opening 29. The numeral sectors are held in their set positions by means of a fixed locking bar 34, which extends in parallel with the rotor shaft, each numeral sector 27 sliding up on said locking bar immediately after completion of the setting operation, the locking bar 34 then engaging with a notch 35 in the inner portion of the numeral sector corresponding to the set up numeral.

For zeroizing the teeth of setting disks after each calculating operation there is provided a separate zeroizing member consisting of a cylindrical segment 36 which partly embraces the rotor when the latter occupies its starting position. For each setting disk the cylinder segment 36 is provided with a circular cam 37, which, in the starting position of the rotor, is positioned under the corresponding setting disk so as to partly embrace the circumference thereof. The cylinder segment 36 is pivoted on two pivots 38 which extend through oblong inclined holes in a flange rigidly connected with the segment, said pivots being fastened in a holder 39. A helical spring 45 strives to pull the cylinder segment to the right so that the latter will normally occupy the lowered position shown in Figure 1. After each calculating operation the rotor is moved so far to the right that its starting position is passed somewhat, the lower end 40 of the lever 24 then engaging with the right end of the flange provided on the cylinder segment, pressing the segment to the left so as to raise the same. Each cam 37 is then moved in an inclined direction upwards towards the corresponding row of teeth, pressing the set teeth in said row to the left so as to cause them to snap back to their inoperative positions. When immediately thereafter the rotor is released, it will be displaced by the spring 23 a few millimeters to the left to its correct starting position, the cylinder segment 36 being then relieved of the pressure from the lever 24 and being pulled back to the right by the spring 45 and lowered to its normal position.

Figure 6 shows schematically another construction of the setting pins. According to said construction each pin 41 is provided with a locking abutment 43 which on account of the pressure from a laterally disposed spring 44 snaps over the edge of the holder 13 when the pin is lifted during the actuation of a key, so that the pin will remain in its set position until it engages with the corresponding tooth or toothed sector. On account of the pressure produced on the engagement with the latter, the tooth 4 will be pressed to the right, as in the example described above, the pin 41 being at the same time pressed to the left so that the locking abutment 43 will slide off the edge, whereupon the pin, through the action of a blade spring 42 engaging the same at its lower end, will be returned to its starting position.

The tens transfer mechanism can be made in an arbitrary known manner. For example, a separate tens transfer rotor provided with tens transfer hooks or the like can be provided in the manner common in calculating machines of the setting disk type.

The totalizer or registering mechanism, with the calculating wheels or intermediate wheels of which the set up teeth are brought into engagement after completed setting operation, is indicated on the drawings through the dot-and-dash circular arc 46 at the upper right hand corner of Figure 3. The registering mechanism and the revolutions counting mechanism can preferably be arranged in a carriage but can also be stationary, if desired.

Through the described construction with only a few, for example four setting pins, the setting mechanism will become very much simplified. The operation of the machine will be convenient because of the very slight key pressure that is required. The provision of setting disk teeth which are shiftable in an axial direction instead of in a radial direction, as in the shown example, will also contribute to the convenient operation and to the simplification and cheapening of manufacture. Of course, different modifications of the embodiment described are conceivable. For example, the setting pins, instead of consisting of pins which are movable in their longitudinal direction, can be made in the form of turnable levers or the like. Furthermore, the rotor can be stationary during the setting operation and instead the holder or support for the setting pins be movable step by step in an axial direction, opposite to the direction of the step-wise movement in the described case. In such a case care must be taken to control that after each setting movement the rotor actually takes up its correct position in respect to the registering mechanism, an extra displacement of the rotor or of the registering mechanism being effected, if necessary.

I claim:

1. In a calculating machine in combination, a rotor, a number of radially projecting and normally inoperative teeth mounted on said rotor in equally spaced apart transverse planes, said projecting teeth being shiftable laterally in relation to the rotor into operative positions, a number of setting members mounted in a transverse row, a keyboard, means under the control of said keyboard for bringing predetermined setting members in positions each in lateral alignment with one of the projecting teeth, an escapement mechanism operable under the control of said keyboard to displace the rotor in a lateral direction in steps equal to the distances between said transverse planes after predetermined ones of said setting members have been positioned and thereby to cause said predetermined setting members to shift the teeth aligned therewith into operative positions without rotation of the rotor, and means for restoring said setting members.

2. An arrangement according to claim 1 in which said setting members consist of spring actuated pins slideable in slots having a lateral width larger than that of the pins, said pins being provided with lateral locking abutments, and stationary stops being provided for engagement with said abutments in the operating positions of the pins so as to retain the pins in these positions, the pins being releaseable upon actuation by contact with corresponding teeth.

TORSTEN LAGERMAN.
